UNITED STATES PATENT OFFICE.

JOHN MELSON, OF WINDSOR, CALIFORNIA.

BOX CONSTRUCTION.

1,216,587.

Specification of Letters Patent. Patented Feb. 20, 1917.

Application filed August 2, 1916. Serial No. 112,636.

To all whom it may concern:

Be it known that I, JOHN MELSON, a citizen of the United States, residing at Windsor, in the county of Sonoma, State of California, have invented a new and useful Box Construction; and I do hereby declare the following to be a full, clear, and exact description of the invention, such as will enable others skilled in the art to which it 10 appertains to make and use the same.

The present invention relates to certain new and useful improvements in reinforcements for boxes and trays and more particularly to a means for reinforcing the ends 15 of a box and securing the side and bottom boards to the end boards, the object of the invention being to provide a device of this character which can be either built into new boxes or applied to old boxes, and which 20 securely fasten the ends of the boxes in position so that they will not split or pull away from the sides and bottom when the box is roughly handled.

The invention is particularly adapted for 25 use in the construction of lug boxes such as are employed in orchards, vineyards, and canneries, and which are submitted to very rough handling. The ordinary lug boxes soon become broken, and on some ranches 30 and estates such a large number of these lug boxes is used that the expense of repairing damaged boxes and replacing those boxes which have been destroyed is quite a big item each year.

35 Further objects of the invention are to provide a sheet metal corner reinforcement for boxes which is comparatively simple and inexpensive in its construction, which enables the members of the box to be securely 40 fastened together so that they will not pull apart, which reinforces the end boards in such a manner as to prevent them from splitting or being broken in, and which can be applied to old damaged boxes, there- 45 by saving many boxes which would otherwise have to be discarded.

With these and other objects in view, the invention consists in certain novel combinations and arrangements of the parts as will 50 more fully appear as the description proceeds, the novel features thereof being pointed out in the appended claims.

For a full understanding of the invention,

reference is to be had to the following description and accompanying drawings, in 55 which:—

Figure 1 is a perspective view of a lug box constructed in accordance with the invention.

Fig. 2 is an enlarged horizontal sectional 60 view through one of the vertical corners of the box.

Fig. 3 is a detail perspective view of one 65 of the corner reinforcements, showing the same as removed from the box.

Fig. 4 is an enlarged vertical sectional view through one of the horizontal corners at the bottom of the box, showing a doubled reinforcing strip in operative position.

Specifically describing the present embodiment of the invention, the numerals 1 designate the end boards of a wooden lug box, 2 the side boards, and 3 the bottom board. The box may be of any suitable or convenient size, and at the top thereof transverse strips 4 may extend across the end 70 boards 1, said strips providing a rest to engage the bottom of a superposed box when a number of boxes are placed in a pile for the purpose of preventing the upper boxes from 75 crushing or bruising the fruit in the lower boxes.

Applied to the ends of the side boards 2 and overlapping the end boards 1 are angular corner strips 5, said strips being conveniently formed of sheet metal and being 80 preferably formed in telescoping sections 5^a and 5^b so that they are extensible and can be adjusted to fit various sizes of boxes. The edges of the telescoping section 5^a are 85 returned at 6 to fit around the edges of the section 5^b which telescopes within the section 5^a. At the top of the box the two flanges or arms of the angular corner strip or stay 5 are formed with extensions 7 which 90 are bent laterally and extend over the upper edges of the end board 1 and side board 2, respectively, said extensions being received under the transverse strip 4, and being engaged by the same nails or fastening members 8 by means of which the transverse strip is secured in position. At the bottom of the box the flange of the corner strip 5 which extends over the end board 1 is formed with an extension 9 which extends 95 laterally above the bottom board 3, while 100 105

the side flange is formed with a somewhat similar extension 10 which is bent over the exterior of the bottom board 3.

The end flange of the angular corner strip 5, or that flange which extends over the side board 2 is formed with a longitudinal slit 11 through which looped strips 12 are inserted. The doubled ends of the looped strips 12 provide eyes 12^a for the reception of wires 13, said wires being arranged on the inside of the box at the vertical corners thereof and having the extremities thereof engaged by the extensions at opposite ends of the angular corner strips 5. The looped strips 12 have a double thickness of metal, and the projecting ends thereof are slit longitudinally to provide a pair of arms 12^b, one of the said arms 12^b of each looped strip being bent around the side of the box, while the opposite arm 12^b of each looped strip is bent over the end of the box. These arms 12^b, as well as the angular corner strips 5, are secured in position by suitable fastening members such as the nails 14. Owing to the fact that the arms 12^b are each of a double thickness of sheet metal, a very strong brace is provided, and it will be obvious that it will be practically impossible for the members of the box to be torn apart under ordinary conditions of use.

A series of the looped strips 12 are also inserted between the lower edges of the end boards 2 and the bottom boards 3, the eyes 12^a at the inner ends of the strips 12 being engaged by transverse wires 15 extending across the bottom of the box at the ends thereof. The bifurcated arms 12^b at the outer ends of these looped strips 12 are bent upwardly over the end boards 1 and downwardly around the bottom board 3, respectively, being secured in position by nails 14. The sides and bottom of the box are thus securely anchored to the end boards 1 by sheet metal strips which are of a double thickness and which can not readily be torn from position. The looped strips or straps 12 are firmly anchored upon the wires 13 and 15 at the inside corners of the box so that it is impossible for the looped strips to pull out of position, and these wires 13 and 15 engage the inner faces of the end boards 1 so as to prevent the end boards from being crushed inwardly or warping out of shape.

In hot weather the wood of which these boxes is constructed shrinks, while the metal expands, so that continuous metal reinforcing strips on the outside of the box buckle under such conditions, providing projections which catch upon other boxes and cause an endless amount of trouble. The present corner stays 5 are formed in telescoping sections which can have the necessary in and out movement to compensate for the shrinkage of the wood and expansion of the metal 65 in hot dry weather. The box as thus con-

structed is rigidly reinforced and can be handled roughly without danger of the corners being broken or the ends being cracked and broken in. The transverse strips 4 at the top of the box provide rigid upper corners well adapted to withstand rough usage, and the various parts of the box are securely fastened together so that it is practically impossible for the box to be pulled apart. There are no metal strips extending over the top of the transverse strips 4, such a construction being objectionable for the reason that when a number of boxes are superposed upon each other, these metal surfaces frequently cause the upper boxes to slip out of position with the result that the fruit in the lower boxes is bruised or crushed.

The reinforcement can also be applied to old boxes which have started to pull apart and which it would otherwise be necessary to discard, thereby saving the expense of providing new boxes. In doing this the transverse strips 4 at the top of the box are removed and the angular corner strips 5 applied to the vertical corners of the box at the outside thereof. There is usually a sufficient looseness between the end boards 1 and side boards 2 to admit of the looped strips 12 being inserted between the same, although if there should not happen to be a sufficient amount of space, this can be readily provided by tapping tightly upon the inner faces of the side boards 2 with a hammer. After the looped strips 12 have been inserted in position the wires 13 are driven through the eyes 12^a thereof, and the various parts of the reinforcement secured in position by the rails 14. In a similar manner the looped strips 12 can be inserted between the end boards 1 and the bottom board 3, the wires 15 subsequently driven into position, and the arms 12^b nailed down after being properly bent around the end and bottom of the box. The transverse strips 4 may then be replaced at the top of the box, and the old box has been reinforced so that it can be again used.

Having thus described the invention, what I claim as new and desire to secure by Letters Patent, is:—

1. A reinforcement for boxes, including doubled strips having the looped ends thereof inserted through corner joints of the box, and anchor means within the box for engaging the said looped ends, the outer ends of the doubled strips providing arms which are bent in opposite directions around the corner of the box.

2. A reinforcement for boxes, including doubled strips having the looped ends thereof inserted through corner joints of the box, and an anchor wire extending along the corner of the box on the interior thereof and engaging the said looped ends of the strips, the outer ends of the doubled strips being

bent in opposite directions around the corner of the box.

3. A reinforcement for boxes, including doubled strips having the looped ends thereof inserted through corner joints of the box, and an anchor wire extending along the corner of the box on the interior thereof for engaging the said looped ends of the strips, the outer ends of the doubled strips being slit longitudinally to provide arms, each of which is of two thicknesses of material, said arms being bent in opposite directions around the corner of the box.

4. A reinforcement for boxes, including an angular corner stay having a slit in one of the flanges thereof, doubled strips inserted through the slit of the corner stay and having the looped ends thereof extending through the corner joint of the box, and anchor means within the box for engaging the said looped ends of the strips, the outer ends of the doubled strips providing arms which are bent in opposite directions around the corner of the box.

5. A reinforcement for boxes, including an angular corner stay having a slit in one of the flanges thereof, doubled strips inserted through the slit of the corner stay and having the looped ends thereof extending through the corner joint of the box, and an anchor wire extending along the corner of the box on the interior thereof and engaging the said looped ends of the strips, the outer ends of the doubled strips providing arms which are bent in opposite directions around the corner of the box.

6. A reinforcement for boxes, including an angular corner stay having a slit in one of the flanges thereof, doubled strips inserted through the slit of the corner stay and having the looped ends thereof extending through the corner joint of the box, and an anchor wire extending along the corner of the box on the interior thereof and engaging the said looped ends of the strips, the outer ends of the doubled strips being slit longitudinally to provide arms, each of which is of two thicknesses of material, said arms being bent in opposite directions around the corner of the box.

7. A reinforcement for boxes, including an angular corner stay having a slit in one of the flanges thereof and provided at its ends with laterally bent extensions, doubled

strips inserted through the slit of the corner stay and having the looped ends thereof extending through the corner joint of the box, and an anchor wire extending along the corner of the box on the interior thereof and engaging the said looped ends of the strips, the extremities of the anchor wire engaging the before mentioned lateral extensions at the ends of the corner stay, and the outer ends of the doubled strips providing arms which are bent in opposite directions around the corner of the box.

8. A reinforcement for boxes, including an angular corner stay formed in telescoping sections and adjustable to the size of the box, one of the side flanges of the corner stay being provided with a slit, doubled strips inserted through the slit of the corner stay and having the looped ends thereof extending through the corner joint of the box, and anchor means within the interior of the box for engaging the said looped ends of the doubled strips, the outer ends of the doubled strips providing arms which are bent in opposite directions around the corner of the box.

9. A reinforcement for boxes, including an angular corner stay formed in telescoping sections and adjustable to the size of the box, one of the side flanges of the corner stay being provided with a slit, and the ends of the corner stay being provided with laterally bent extensions, doubled strips inserted through the slit of the corner stay and having the looped ends thereof extending through the corner joint of the box, and an anchor wire extending along the corner of the box on the interior thereof and engaging the looped ends of the doubled strips, the extremities of the anchor wire being engaged by the before mentioned laterally bent extensions at the ends of the corner stay, and the outer ends of the doubled strips providing arms which are bent in opposite directions around the corner of the box.

In testimony whereof I have signed my name to this specification in the presence of two subscribing witnesses.

JOHN MELSON.
